2,437,045

DETERMINATION OF HYDROCARBON CONCENTRATION IN SOIL SAMPLES

Edwin E. Roper, Tulsa, Okla., assignor to Standard Oil and Gas Company, Tulsa, Okla., a corporation of Delaware

Application April 24, 1944, Serial No. 532,427

5 Claims. (Cl. 23—232)

1

This invention relates to geochemical prospecting in which samples from the earth are used to determine the presence and location of subterranean petroliferous deposits. More particularly the present invention relates to a method of analyzing samples of soil or rock to evaluate the concentration of the upwardly diffusing petroliferous material arising from said subterranean deposits. The presence of said material in the soil sample is an indication of underlying relatively deep-seated petroliferous deposits. When using the method of the present invention, the concentration of such material found at or near the surface of the earth accurately reflects the lateral extent of the deep-seated petroliferous deposit.

It is well known to analyze samples of the soil by physico-chemical decomposition methods to determine the presence and quantity of hydrocarbons in the soil, said hydrocarbons originating primarily from an underlying petroliferous deposit. However, the quantity of hydrocarbon found in the soil sample can not, in general, be directly utilized as a geochemical prospective index. The reason for this is to be found in the widely varying sorptive capacities of different soil or rock samples. This is explained in detail in U. S. Patent 2,165,440, which describes a method for ascertaining the sorptive capacity of each individual soil sample whereby the quantity of hydrocarbon found in each sample may be corrected to compensate for the varying sorptive capacities. This patent teaches that the sorptive capacity of each soil sample must be determined in order to correct the corresponding hydrocarbon concentration if a reliable survey is to be obtained. This is necessary so that all the soil samples of the geochemical survey will be on a strictly comparable basis. The corrected values of hydrocarbon concentration will then truly reflect the position of the subterranean petroliferous deposit, since said corrected values are directly related to the partial pressure of the upwardly-migrating hydrocarbons. According to the procedure described in the patent, it should be noted that the properties of the soil cancel out, and in effect, the soil itself serves merely as an intermediate or as a transfer medium.

The prior processes of analysis of soil samples by physico-chemical decomposition, however, involve numerous disadvantages. According to said prior-known processes, the hydrocarbons sorbed in the soil sample are removed either by the application of a vacuum, as described in my U. S. application S. N. 378,785, by the application of heat, as described in U. S. Patent 2,212,681, issued to T. H. Dunn, by means of a stream of sweeping gas, as described in my U. S. application S. N. 452,842, by the addition of a suitable chemical reagent, or by the various possible combinations

2

of these four methods. The recovered hydrocarbons are subsequently determined by analysis employing means well known to those skilled in the art. One of the principal objections to such methods is that there is no certainty that all of the sorbed hydrocarbons are completely removed, for in most instances it is exceedingly difficult to completely remove all of the sorbed hydrocarbons even when excessive temperatures, prolonged evacuation, or numerous consecutive extractions are employed. If too high temperatures are utilized in an attempt at more thorough removal, pyrolysis of the hydrocarbons takes place, giving rise to erroneous results. In addition to analyzing each soil sample for sorbed hydrocarbons it is generally necessary to determine the sorptive capacity of each soil sample thus prolonging the time and effort required.

It is therefore an object of the present invention to provide a process in which a true and reliable prospecting index may be determined by performing but one type of measurement on the soil sample. An additional object is to provide a process in which variations due to the sorptive capacities of the soil are inherently and automatically overcome. A further object of the present invention is to provide a process which may be carried out at normal temperatures so that changes in the nature of the hydrocarbons due to pyrolysis can not take place. Still another object of the present invention is to provide a process which may be carried out more easily and simply than previously-known processes, and which will give results that are more accurate and reliable than heretofore.

Fundamentally, the process of the present invention is a synthetic method of analysis, contrasted to those previously-known, which are all decomposition methods. A portion of a soil sample after collection is immersed in an artificial atmosphere containing a known quantity of hydrocarbons and after a suitable period of time the amount of hydrocarbon in the artificial atmosphere is measured by some means. The gain or loss of hydrocarbon in the artificial atmosphere is then a measure of the disparity of the partial pressure of the hydrocarbon in the artificial atmosphere and that of the equilibrium pressure of the hydrocarbon sorbed on the soil sample. By repeating the measurement with a second fresh portion of the soil sample and an artificial atmosphere containing a different known partial pressure of hydrocarbon, the true partial pressure of the sorbed hydrocarbon in the original soil sample can be computed. It can be seen that as close an approach to the true partial pressure can be established as is desired by repeating such measurements many times. However, it has been found that this is not generally necessary and that from two to four meas-

urements are all that are required. Alternatively, a method may be employed in which concurrent determinations are made rather than consecutive determinations. This method has been termed an equilibration method, whereby a successive approximation approach to the true equilibrium conditions of the sorbed hydrocarbon gas in situ is obtained.

It will be appreciated from this description of the general method of operation of the present invention that the properties of the soil cancel out, and in effect, the soil merely serves as an intermediate or as a transfer medium. This is somewhat analogous to the process described in U. S. Patent 2,165,440 in principle but the method of the present invention accomplishes this and an additional step in one simple, direct measurement. In addition, the data secured in the application of the present method permits the sorptive capacity of the soil to be computed if this proves necessary and helpful.

The following description is a preferred technique which will permit one skilled in the art to reproduce the method in accordance with the concept of the present invention. However, nothing herein is to be construed as limiting the scope of the present invention to the preferred technique, since the same fundamental operations may be accomplished by other means.

The drawing illustrates an example of an apparatus which can be used for carrying out the process described hereinafter. The artificial atmospheres may be prepared by adding any known amounts of hydrocarbons to inert gas such as nitrogen, helium, argon, hydrogen, or air, the first named being preferred. It is advantageous to initially analyze the atmospheres by the same method as is subsequently used for determining the hydrocarbon concentration of the atmosphere after equilibrium with the soil sample has been obtained. Theoretically, in order to avoid loss of water in the soil sample and consequently change the sorptive capacity of the soil, the partial pressure of water vapor in the artificial atmosphere should be equal to the equilibrium partial pressure of the water over the soil sample. Actually, it has been found that after the artificial atmosphere is saturated with water vapor no erroneous results will occur. The artificial atmosphere can be easily saturated with water vapor by passing the inert gas through water. According to the preferred method of the present invention three artificial atmospheres are used, containing respectively, 30, 60, and 120 P. P. M. (parts per million) of hydrocarbon.

After a soil sample has been collected and divided into separate portions, one of the portions is hermetically sealed in a container and subjected to a vacuum for a short interval of time in order to deaerate the soil sample.

Following the deaeration a known amount of one of the artificial atmospheres is introduced into the container. The soil sample is permitted to remain several hours to several days. It has been found that a period of 18 hours is highly satisfactory for the purposes of the present invention. At the end of this period of time, the hydrocarbons sorbed on the soil sample are in substantial equilibrium with the hydrocarbons in the artificial atmosphere. The concentration of hydrocarbons in the atmosphere is then determined by any well-known method and this new concentration is compared with the original concentration of hydrocarbons in the artificial atmosphere. Whenever there is a decrease in the

concentration of hydrocarbons in the artificial atmosphere it will be known that the original concentration in the artificial atmosphere was greater than the gas equilibrium concentration of sorbed hydrocarbons on the soil sample. This will be true, since the soil sorbed some of the hydrocarbons originally contained in the artificial atmosphere. The same procedure is followed with another portion of the same soil sample, the concentration of hydrocarbons in the artificial atmosphere, however, being reduced or increased. If the concentration of hydrocarbons is reduced, for example, and it is found, after substantial equilibrium has been obtained, that the concentration of hydrocarbons in the artificial atmosphere is greater than the original concentration, then it will be known that the gas equilibrium concentration of the soil sample was greater than the original concentration of hydrocarbons in the artificial atmosphere. By interpolating the data so obtained it is possible to compute that concentration of hydrocarbons in an artificial atmosphere, which would undergo no change during the period of time for establishing substantial equilibrium and which therefore corresponds to the true equilibrium condition of the sorbed hydrocarbon gas in situ. In other words, the original sorption equilibrium pressure of the gaseous hydrocarbons contiguous with the phase sorbed on the soil when it was in the earth may be ascertained.

While it is also desirable to use a hydrocarbon atmosphere containing hydrocarbons which are of substantially the same type as those contained in the sample of soil, this also is not essential. Such a refinement, however, can be carried out by testing a portion of the soil sample qualitatively before carrying out the method of the present invention. Highly satisfactory and accurate results, however, can be obtained by using a hydrocarbon atmosphere containing known concentrations of pure alkanes such as propane, butane, pentane, hexane, heptane, or suitable mixtures of the same. Obviously the temperature of the equilibrium step must be such that the hydrocarbons in the atmosphere are in the gaseous state. For this reason it may be more desirable to use hydrocarbons which are normally gaseous, or have appreciable vapor pressure, at normal temperatures, such as propane, butane or pentane.

The data presented in Table 1 show how the concentration, in parts per million, of the hydrocarbons sorbed on the soil sample may be computed. On occasion the desired information may be indicated as the partial pressures of the hydrocarbons in the hydrocarbon atmosphere rather than the concentration in parts per million. Such partial pressures may be obtained by multiplying the concentration C by a factor, 0.76, according to known physical laws.

Table I

Expt. No.	Concentration of C_6H_{12} in B. P. M. (by volume)		$\Delta c = c - C$ P. P. M.	p , Partial pressure of C_6H_{12} in gas phase at equilibrium μ
	c , of original artificial atmosphere	C , of artificial atmosphere after equilibration		
1	30	33	-3	25.1

By interpolation		43	0	32.7

$75 \quad 1 p = C \times 10^{-6} \times 760 \times 10^3 = 0.76 C; p \text{ in } \mu.$

With reference to the drawing, which illustrates one form of apparatus for carrying out the above-described process, a portion of a soil sample is weighed (M_0 grams) into container 11 which is then connected to the apparatus at 12. Now, in order to determine the free gas space in container 11, v_F , stopcocks 13, 14, 15, 16, 17, 18, 19, and 21 are closed. Stopcock 19 is then slowly opened so as to establish communication with a vacuum pump or the like (not shown) until the pressure indicated on manometer 23 decreases from the prevailing barometric pressure to about 1 mm. This probably takes about two minutes and the pressure is maintained at about 1 mm. for an additional two minutes to completely evacuate the system. Stopcocks 18 and 22 are then closed. Helium is then introduced into the system by opening stopcock 14 until a high pressure of about 760 mm. is indicated by manometer 23. The volume V_a of the space defined by stopcock 22, calibration mark 24 on manometer 23, stopcocks 14, 19, 21 and 16 is known from a previous calibration. After the helium pressure has been built up, stopcock 14 is closed and the pressure, P_2 , is measured on manometer 23. The ambient temperature t_2 is also measured and recorded. Stopcock 22 is then opened and the helium is permitted to expand into container 11. This pressure, P_3 , and the ambient, t_3 , is determined and recorded. From this data the volume of v_F may be calculated from the equation:

$$v_F = \frac{v_a(P_2 - P_3)}{P_3}$$

Following the determination of the volume v_F , stopcock 19 is opened and the helium is withdrawn from the system by a vacuum pump or the like until the pressure drops to about 1 mm., as indicated on manometer 23. Stopcocks 19 and 22 are then closed. Stopcock 15 is then opened to permit water to flow into flask 25 containing an artificial atmosphere so that a pressure exceeding 760 mm. will be created therein. Stopcock 15 is then closed, and stopcocks 16 and 21 are opened so that a suitable pressure of about 700 mm. is built up in gas-sampler flask 26. Flask 26 is then detached at 27, after closing stopcocks 21 and 20. The contents of flask 26 are then analyzed by any suitable method in order to determine the concentration c_4 of hydrocarbons in the artificial atmosphere contained in flask 25. This concentration is determined in P. P. M. (parts per million).

Stopcocks 22 and 16 are opened so as to build up a suitable pressure in the container 11. The pressure, P_4 , is measured on manometer 23. The artificial atmosphere is permitted to remain in contact with the soil sample in container 11 for a suitable period of time, for example, 18 hours, so that equilibrium will be established. During this time gas-sampler flask 26 is reconnected to connector 27 and is evacuated thru stopcock 18, which is then closed. After the period for establishing equilibrium, stopcock 21 is opened and the gas in container 11 is permitted to expand into gas-sampler flask 26. If desirable or necessary, stopcock 13 may be opened so that the gases may be positively expelled from container 11. After the expansion of the gases, stopcock 21 is closed and the pressure, P_5 , is measured on manometer 23. Stopcock 20 is then closed, flask 26 removed from connector 27, and the contents of flask 26 are analyzed for hydrocarbon concentration, C_4 , as before. If desired, the hydrocarbon concentration can be determined by the

method described in my U. S. application S. N. 452,842.

The procedure described above may be repeated again or several times, using fresh portions of the same soil sample and artificial atmospheres having different hydrocarbon concentrations c_5 , c_6 , etc., thus obtaining the value of C_5 as explained above. For calculating the true, original, in situ, concentration of gaseous hydrocarbons in the soil sample, C_0 , the following equation may be solved:

$$C_0 = \frac{c_5 C_4 - c_4 C_5}{c_5 - c_4 - C_5 + C_4}$$

15 The foregoing equation will give the desired concentration providing a linear relationship exists between c and C . Obviously, if such a relationship does not hold true, several tests, for example, five or six, should be run and suitable corrections applied.

20 If desired, the relative sorptive index may be determined from the data and results obtained in the foregoing procedure by methods known to those skilled in the art.

25 Having now described my invention and a manner of carrying out same, what I claim is:

1. A method for determining an index of the concentration of hydrocarbons sorbed on a soil sample, comprising subjecting each of a plurality of de-aerated, substantially similar portions of said soil sample to an artificial atmosphere, each of said atmospheres initially containing a different known concentration of hydrocarbons, maintaining each of said atmospheres in contact with 30 the corresponding portion of said soil sample for a substantial period of time sufficient to establish substantial equilibrium between the partial pressures of the hydrocarbons in the artificial atmosphere and the hydrocarbons sorbed on the soil sample, then determining the concentration of hydrocarbons in each of said atmospheres, whereby said index may be determined.

2. A method for determining an index of the concentration of hydrocarbons sorbed on a soil 45 sample, comprising removing air from a plurality of substantially similar portions of said soil sample, subjecting each portion to an artificial atmosphere for a substantial period of time sufficient to establish substantial equilibrium between the partial pressures of the hydrocarbons in the artificial atmosphere and hydrocarbons sorbed on the soil sample, each of said atmospheres initially containing a different known concentration of hydrocarbons, and determining the change in concentration 50 of hydrocarbons in each atmosphere after said substantial period of time, whereby an index may be determined.

3. A method for determining an index of the concentration of hydrocarbons sorbed on a soil 55 sample, comprising removing air from a first portion of a soil sample, subjecting said first portion to a first artificial atmosphere for a substantial period of time sufficient to establish substantial equilibrium between the partial pressures of the hydrocarbons in the artificial atmosphere and the hydrocarbons sorbed on the soil sample, said first atmosphere initially containing a known concentration of hydrocarbons, removing air from at least one other portion of said soil sample, subjecting each of said at least one other portion to an atmosphere for a period of time equal to said first-mentioned period of time, each of said atmospheres initially containing a concentration of hydrocarbons different from each other and from said first atmosphere, and determining the

60 65 70 75

concentration of hydrocarbons in each atmosphere, whereby an index may be determined.

4. A method for determining an index of the concentration of hydrocarbons sorbed on a soil sample comprising removing air from a first portion of said soil sample, subjecting said first portion to a first artificial atmosphere for a substantial period of time sufficient to establish substantial equilibrium between the partial pressures of the hydrocarbons in the artificial atmosphere and the hydrocarbons sorbed on the soil sample, said first atmosphere initially containing a known concentration of hydrocarbons, removing air from at least two other portions of said sample, subjecting each of said portions to an atmosphere for a period of time equal to said first-mentioned period of time, one of said atmospheres containing an initial concentration of hydrocarbons higher than said first atmosphere and at least one of the other of said atmospheres initially containing a concentration of hydrocarbons lower than said first atmosphere, and determining the concentration of hydrocarbons in each atmosphere, whereby an index may be determined.

5. A method for determining an index of the concentration of hydrocarbons sorbed on a soil sample, comprising dividing said soil sample into at least two portions, removing air from said por-

tions, subjecting each of said portions to artificial atmospheres for equal substantial periods of time sufficient to establish substantial equilibrium between the partial pressures of the hydrocarbons in the artificial atmosphere and hydrocarbons sorbed on the soil sample, each of said atmospheres initially containing different known concentrations of hydrocarbons, the concentration of hydrocarbons in one of said atmospheres being higher than the expected concentration of hydrocarbons sorbed on said soil sample and the concentration of hydrocarbons in at least one of said other atmospheres being lower than the expected concentration of hydrocarbons sorbed on said sample and determining the concentration of hydrocarbons in each atmosphere after said substantial period of time, whereby an index may be determined.
